(57) **CLAIM**

The ornamental design for a square bottle, as shown and described.

DESCRIPTION

FIG. 1 is a top, front, and left side perspective view of a first embodiment of a square bottle of the present invention.

FIG. 2 is a front elevational view thereof, the rear elevational view being a mirror image except for the unclaimed thread.

FIG. 3 is a front, left side corner view thereof.

FIG. 4 is a left side, rear corner view thereof.

FIG. 5 is a right side elevational view thereof, the left side elevational view being a mirror image except for the unclaimed thread.

FIG. 6 is a top plan view thereof.

FIG. 7 is a top, front, and left side perspective view showing a second embodiment of a square bottle of the present invention.

FIG. 8 is a front elevational view thereof, the rear elevational view being a mirror image except for the unclaimed thread.

FIG. 9 is a front, left side corner view thereof.

FIG. 10 is a left side, rear corner view thereof.

FIG. 11 is a right side elevational view thereof, the left side elevational view being a mirror image except for the unclaimed thread; and,

FIG. 12 is a top plan view thereof.

The broken lines shown in the drawings are included for the purpose of illustrating environmental structure that forms no part of the claimed design.
